US00D849680S

(12) **United States Design Patent** (10) **Patent No.:** **US D849,680 S**
(45) **Date of Patent:** **** May 28, 2019**

(54) **RECHARGEABLE BATTERY**

(71) Applicant: **Sony Corporation**, Tokyo (JP)

(72) Inventor: **Masaharu Nakashima**, Kanagawa (JP)

(73) Assignee: **SONY CORPORATION**, Tokyo (JP)

(**) Term: **15 Years**

(21) Appl. No.: **29/585,724**

(22) Filed: **Nov. 28, 2016**

Related U.S. Application Data

(63) Continuation of application No. 29/466,238, filed on Sep. 5, 2013, now Pat. No. Des. 772,804.

(51) **LOC (11) Cl.** **13-02**

(52) **U.S. Cl.**

USPC **D13/103**

CLAIM

The ornamental design for a rechargeable battery, as shown and described.

DESCRIPTION

FIG. 1 is a front, top, left perspective view of a rechargeable battery showing my new design;

FIG. 2 is a rear, top, left perspective view thereof;

FIG. 3 is a front elevational view thereof; and

FIG. 4 is a top plan view thereof.

FIG. 5 is a rear elevational view thereof;

FIG. 6 is a left side elevational view thereof;

FIG. 7 is a right side elevational view thereof; and

FIG. 8 is a bottom plan view thereof.

FIG. 9 is a front, top, left perspective view of a second embodiment of a rechargeable battery showing my new design;

FIG. 10 is a rear, top, left perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and,

FIG. 16 is a bottom plan view thereof.

The even-dash broken lines form no part of the claimed design. The dot-dash broken lines that define the boundaries of the claimed design form no part of the claimed design.
